UNITED STATES PATENT OFFICE

2,561,399

INKING MECHANISM

Gordon Montgomery, Wexford, Pa., assignor to
Miller Printing Machinery Co., Pittsburgh, Pa.,
a corporation of Pennsylvania

Application September 10, 1948, Serial No. 48,581

10 Claims. (Cl. 101—352)

1

This invention relates to inking mechanism, particularly inking mechanism for printing presses. It has to do with inking mechanism which is movable into and out of cooperative relationship with the form rollers of a printing press, such, for example, as inking mechanism of the so-called "rollaway" type.

Inking mechanism is well known which can be bodily removed or rolled away from a printing press with which the inking mechanism is adapted to be used to facilitate work on the press when the press is not being used for printing, as, for example, when a form is being made ready, and also to provide for cleaning and repair of parts of the press and inking mechanism. The form inking rollers are mounted in the press and the inking mechanism which delivers ink from the ink fountain to the form rollers is separated from the form rollers when it is moved away. The inking mechanism comprises an ink fountain and suitable means for working up the ink and delivering the worked up ink to the form rollers, which means may include an ink drum, a doctor roller or rollers between the ink fountain and the ink drum, a vibrator roller or rollers cooperating directly with the form rollers and an ink transfer roller or rollers between the ink drum and the vibrator roller or rollers.

It is frequently necessary when the inker is disposed in its inoperative position away from the press to remove the form rollers in order to gain access to portion of the press to be worked on. The form rollers are mounted in the press in position to ink the form during operation of the press. The working surfaces of the form rollers are either composition or rubber and, of course, are covered with ink. They cannot be set down on their working surfaces because the rollers would thereby be deformed and because anything coming in contact with the working surfaces of the form rollers would be smeared with ink. It has been necessary to specially provide a place to dispose the form rollers when they have been removed so that they are supported by their shafts with their working surfaces out of contact with the support. Moreover the form rollers are long and heavy, particularly in the larger sized presses, and it has generally been necessary for two men working together to remove the form rollers individually one after the other. When the form rollers are replaced they have to be replaced in similar fashion. Thus a very considerable amount of work has been required to remove and replace the form rollers in addition to the fact that it has been necessary to

2

specially provide a place to dispose the form rollers when removed from the press so that they will be supported by their shafts at the ends of the rollers instead of upon their working surfaces.

5 I have devised inking mechanism which is movable into and out of cooperative relationship with respect to the press, i. e., into and out of position to deliver ink to the form rollers, and which may be so operated that when desired the form rollers may be automatically removed from the press and carried along with the inker. Thus the problem of removing and disposing the form rollers as above explained is obviated, it being unnecessary to even so much as touch the form rollers by hand when it is desired to remove them along with the inking mechanism. When the form rollers are removed along with the inking mechanism they are supported by their shafts at the ends thereof and are maintained out of contact with all other rollers. They are not set down on their working surfaces so there is no danger of their becoming deformed or of smearing ink upon any supporting device.

I provide inking mechanism comprising a support, form roller means carried thereby and removable therefrom, means for delivering ink to the form roller means, the ink delivering means being movable into and out of location adjacent the form roller means when carried by the support, and means movable to operative position to engage the form roller means and remove the same from the support upon movement of the ink delivering means out of said location and movable to inoperative position wherein it has no effect on the form roller means upon movement of the ink delivering means out of said location. The support mentioned may be the bearings in which the form roller means are mounted; such bearings may be so constructed and arranged that the form rollers may be removed therefrom and carried along with the ink delivering means when the latter is moved away from the press. The form roller bearings may be upwardly open and the form rollers may be lifted upwardly out of the bearings upon movement of the ink delivering means out of operative position relatively to the form roller means.

The ink delivering means may be shiftable by movement comprising substantially horizontal movement into and out of location adjacent the form roller means when carried by the support and the form roller means may be removed from the support upon shifting of the ink delivering means out of said location. The ink delivering means may be shiftable by movement comprising

movement substantially along a track into and out of location adjacent the form roller means and the form roller means may be removed from the support upon such shifting of the ink delivering means. Rack and pinion means may be provided for shifting the ink delivering means into and out of location adjacent the form roller means.

During movement into and out of location adjacent the form roller means the ink delivering means may be angularly displaceable; means are preferably provided which are movable to operative position to engage the form roller means and remove the same from the support upon angular displacement of the ink delivering means and movable to inoperative position wherein it has no effect on the form roller means upon angular displacement of the ink delivering means. The ink delivering means may have a portion which during movement of the ink delivering means into and out of location adjacent the form roller means is generally vertically displaceable and means may be carried by said portion of the ink delivering means movable to operative position to engage the form roller means and remove the same from the support upon generally vertical movement of said portion of the ink delivering means and movable to inoperative position wherein it has no effect on the form roller means upon generally vertical displacement of said portion.

The ink delivering means may during movement into and out of location adjacent the form roller means be sequentially angularly and linearly displaceable and may upon angular displacement remove the form roller means from the support therefor.

I preferably provide an operating member mounted on the ink delivering means and means for shifting the operating member relatively to the ink delivering means between operative position wherein the operating member is adapted to engage the form roller means and remove the same from the support upon movement of the ink delivering means out of location adjacent the form roller means and inoperative position wherein the operating member has no effect on the form roller means upon movement of the ink delivering means out of said location.

The ink delivering means may be turnable into and out of location adjacent the form roller means when carried by the support and an operating member may be mounted on the ink delivering means shiftable to position to engage the form roller means and remove the same from the support upon turning of the ink delivering means out of said location so that when desired the form roller means may be carried with the ink delivering means.

Other details, objects and advantages of the invention will become apparent as the following description of a present preferred embodiment thereof proceeds.

In the accompanying drawings I have shown a present preferred embodiment of the invention in which

Figure 1 is an elevational view of inking mechanism and a portion of a printing press with which the inking mechanism is cooperable, the inking mechanism being shown in operative position with respect to the press;

Figure 2 is a view similar to Figure 1 showing the inking mechanism in angularly displaced position ready to be moved away from the press while leaving the form rollers in position in the press;

Figure 3 is a view similar to Figures 1 and 2 showing the inking mechanism removed from the press with the form rollers remaining in position in the press;

Figure 4 is a view similar to Figure 2 but showing the form rollers removed from their bearings and supported by the inking mechanism in position to move away from the press along with the inking mechanism;

Figure 5 is a fragmentary plan view to enlarged scale of a portion of the mechanism; and

Figure 6 is a vertical longitudinal cross-sectional view taken on the line VI—VI of Figure 5.

My invention is embodied in the apparatus shown in the drawings, which apparatus is the same apparatus as is shown in the drawings of an application of Raymond K. Holtz, Serial No. 48,556, filed of even date herewith.

Referring now more particularly to the drawings, there is shown a printing press designated generally by reference numeral 2 which may be of conventional flat bed and cylinder type and which may operate in normal manner in printing. Since the invention is concerned only with the inking mechanism the remainder of the press is not shown. The press has adjacent opposite sides thereof and extending longitudinally of the press in parallel relation bars 3 each carrying brackets 4, the brackets 4 being arranged in opposed pairs as shown in Figure 5. There are as many pairs of brackets 4 as there are form rollers in the press. Each bracket 4 is slidable along the bar 3 which carries it so as to assume a desired adjusted position on the bar and is fastened in such position by a set screw 5.

Each bracket 4 has a portion 6 projecting inwardly of the press from the bar 3 carrying the bracket and which carries at its inner end an upwardly open form roller bearing 7 vertically adjustable by an adjusting screw 8. The bearings 7 are thus disposed in transversely aligned pairs as shown in Figure 5, each being adapted to have a form roller shaft portion to be carried thereby disposed therein by generally downward movement and removed therefrom by generally upward movement.

There are shown two form rollers 9. Any desired number of form rollers may be employed, one or more. Each form roller has an enlarged central or working portion 10, necks 11 at both ends of the portion 10 and shaft portions 12 at the ends of the roller connected with the necks 11, the shaft portions 12 being, when the form rollers are in use, journaled in the bearings 7. Each shaft portion 12 extends outwardly beyond the outer edge of the corresponding bearing 7 as shown in Figure 5. The press bed which carries the type form moves under and in contact with the bottoms of the portions 10 of the form rollers, the form rollers thus inking the form. Ink is delivered to the form rollers by ink delivering means now to be described.

The inking mechanism comprises a frame having opposed frame members 13 which extend in generally vertical planes parallel to each other.

The frame members 13 are suitably fastened together by cross members not shown. Journaled in the frame members 13 is a shaft 14. Adjacent opposite ends of the shaft 14 and disposed inside the respective frame members 13 are pinions 15 which are keyed to the shaft 14. The press frame 2 has an extension 16 which comprises opposed portions extending longitudinally of the press beneath the pinions 15, each such portion having fastened to its upper surface an upwardly facing rack 17 with which one of the pinions 15 meshes,

the inker frame comprising the frame members 13 and the mechanism carried thereby being partially supported by the press frame extension 16 through the racks 17. As will presently appear the inker frame may be bodily angularly displaced about the axis of the shaft 14.

The opposed portions of the press frame extension 16 also have tracks 18 and each of the inker frame members 13 carries a roller 19 adapted during movement of the inker toward and away from the press, as will be presently explained, to ride on one of the tracks 18. At the right hand end of each track 18, viewing Figures 1, 2, 3 and 4, there is a track extension member 20 which is vertically movable and which when in its uppermost position has its upper surface at the level of the upper surface of the corresponding track 18 and in longitudinal alignment therewith so as in effect to form a short extension of the track. Each extension member 20 has a sleeve 21 projecting downwardly therefrom through which passes a bolt 22 having a head 23. Each member 20 has a socket 24 receiving the head 23 of the corresponding bolt 22, upward movement of the member 20 being limited by engagement of the bottom of the socket 24 with the under surface of the bolt head 23. Each bolt 22 and sleeve 21 are disposed within a bore 25 in the press frame extension 16 and each bolt 22 is screwed into the press frame extension. A compression coil spring 26 is confined in the bottom of the bore and presses upwardly against the bottom surface of the sleeve 21 so as normally to maintain the member 20 in its uppermost position as shown in Figures 2, 3 and 4. The springs 26 are strong enough to hold the members 20 in their uppermost positions when the rollers 19 and the mechanism connected therewith are supported by the members 20 as shown in Figures 2 and 4.

Journalized in the inker frame is a transverse shaft 27 to one end of which is fastened by a pin 28 a handle 29 for turning the shaft. Adjacent its opposite ends and within the inker frame members 13 the shaft 27 carries eccentrics 30. The press frame 2 has extensions 31 each disposed above one of the eccentrics 30 having a vertically oriented tapped hole into which is threaded a bolt 32 having a head 33, a nut 34 being adapted to be threaded onto each bolt 32 and turned up against the corresponding extension 31 to maintain the bolt in adjusted position. Each extension 31 is counterbored at 35 to provide clearance for the bolt head 33 upon vertical adjustment of the bolt. When the inker is in operative position relatively to the press each of the eccentrics 30 is adapted to engage the bottom surface of the corresponding bolt head 33. But at the same time the respective rollers 19 are disposed upon the track extensions 20. With the parts thus disposed turning of the handle 29 causes rotation of the shaft 27 and of the eccentrics 30. Since the eccentrics 30 engage the lower surfaces of the bolt heads 33 and since the bolts 32 are fixedly positioned in the press frame extensions 31 turning of the eccentrics 30 causes angular displacement of the inker frame in the clockwise direction viewing Figure 1, such angular displacement being accompanied by downward depression of the track extension 20 by the rollers 19 which are disposed thereupon as shown in Figure 1. When the inker frame has been thus angularly displaced about the axis of the shaft 14 the inker is in operative relationship with respect to the press and the ink delivering means, presently to

be described, are in position to deliver ink to the form rollers 9.

The ink delivering means comprises an ink fountain 36 having a fountain roll 37 for delivering ink from the ink fountain in usual manner. The fountain roll 37 is keyed to a shaft 38 disposed generally above the shaft 14. There is provided the usual ink drum 39 and a ductor roller 40 for transferring ink from the fountain roll 37 to the ink drum 39. Ink on the ink drum 39 is worked up by rollers 41 and 42, the latter transferring ink to the vibrator roller 43 which in turn seats in the saddle between the two form rollers 9 and transfers the ink to the form rollers. The ink transferring and working up functions may be performed in conventional manner and the invention is not dependent upon any particular arrangement of ink delivering means. It is sufficient to point out that when the inker is in operative position relatively to the press as shown in Figure 1 the vibrator roller 43 seats in the saddle between the form rollers 9 and delivers ink thereto.

With the parts in operative position as shown in Figure 1, when it is desired to roll the inker away from the press the handle 29 is operated to turn the shaft 27 through approximately 180° which in turn rotates the eccentrics 30 through a similar angle so that the high points of the eccentrics are disposed downwardly relatively to the axis of the shaft 27 as shown in Figures 2, 3 and 4. Such turning of the shaft 27 is accompanied by upward movement of the track extensions 20 under the action of the compression coil springs 26, the members 20 being stopped when their upper surfaces are in alignment with the upper surfaces of the tracks 18 by the bolt heads 23 as above explained. But upward movement of the members 20 causes consonant upward movement of the rollers 19 which at the time rest upon the members 20, and such upward movement of the rollers 19 in turn causes angular displacement of the inker about the axis of the shaft 14 from the position shown in Figure 1 to the position shown in Figures 2 and 4. Such angular displacement of the inker raises the vibrator roller 43 out of contact with the form rollers 9 and so that its lowermost point is above the uppermost points of the form rollers 9, thus providing for movement of the inker toward the left away from the press without interference between the vibrator roller and the form rollers. Movement of the inker away from the press is accomplished by turning the shaft 14 by means presently to be described. Since the pinions 15 are keyed to the shaft 14 and mesh with the stationary racks 17 turning of the shaft 14 in the counterclockwise direction viewing Figure 1 causes the pinions 15 to turn relatively to the racks 17 and hence the inker frame and everything carried thereby is bodily linearly displaced toward the left. During such displacement of the inker the rollers 19 ride upon the tracks 18. The inker is shown in position spaced from the press in Figure 3.

When it is desired to return the inker to operative position the shaft 14 is turned in the clockwise direction until the inker assumes the position of Figures 2 and 4 whereupon the shaft 27 is turned through approximately 180° to cause the eccentrics 30 to angularly displace the inker back to the position of Figure 1 with the vibrator roller 43 in engagement with the form rollers 9 so as to deliver ink thereto.

Extending through the inker frame from side to side is a shaft 44. The shaft 44 projects out-

wardly at at least one side of the inker and has fastened thereto an operating handle 45 for turning the shaft. Projecting from the inker frame member 13 at the side where the operating handle 45 is disposed are two stop pins 46 for limiting turning of the shaft 44 by engaging the handle 45. The pins 46 permit turning of the shaft 44 through approximately 180°.

Connected with each of the inker frame members 13 is a stud 47, the shaft 44 and the stud 47 at each side of the inker frame serving as supports and guides for a slide 48. Each of the opposed slides 48 has a slot 49 receiving the corresponding stud 47 and an open ended slot 50 receiving the shaft 44. Thus each slide 48 is supported and guided by the shaft 44 and one of the studs 48 for movement longitudinally of the inker frame.

The shaft 44 has fastened thereto at a point spaced slightly inwardly from each of the inker frame members 13 a disc 51 having flattened upper and lower faces 52. Pivoted to each disc 51 by a pin 53 is a somewhat L-shaped link 54 pivoted to one of the slides 48 at 55. Each slide 48 is movable between a position toward the right as shown in Figures 1, 4, 5 and 6 and a position toward the left as shown in Figures 2 and 3. When the handle 45 is in the position shown in Figure 5 in contact with the upper surface of the right hand pin 46 the slide is toward the right. When the handle 45 is turned through approximately 180° so as to turn the shaft 44 in the counterclockwise direction viewing Figures 1, 2, 3, 4 and 6 through approximately 180° the slides 48 are by the links 54 pulled toward the left to the position in which they are shown in Figures 2 and 3. The links 54 are bent so as to enable them to extend around the shaft 44 when the parts are in the position shown in Figures 2 and 3.

As shown in Figure 5 the slides 48 are disposed against the inner surfaces of the inker frame members 13 and are spaced slightly outwardly from the vertical plane containing the ends of the shaft portions 12. Each of the slides 48 carries inwardly projecting lifting members 56 which are spaced apart on centers a distance equal to the horizontal distance between the axes of the form rollers and, when the parts are in the position of Figures 1, 4, 5 and 6, directly underlie the ends of the shaft portions 12 as shown in Figure 5. With the parts thus positioned the lifting members 56 are spaced slightly below the respective shaft portions 12. Each of the lifting members 56 has in its upper surface a channel 57 of the same curvature as the shaft portions 12 so that upon upward movement of the lifting members 56 relatively to the form rollers 9 the lifting members will engage the under surfaces of the shaft portions 12 adjacent the ends of the form rollers and raise the form rollers upwardly so that the shaft portions 12 rise out of the upwardly open bearings 7. When the slides are in the position shown in Figures 1, 4, 5 and 6 and the shaft 27 is turned to permit angular displacement of the inker in the counterclockwise direction about the axis of the shaft 14 viewing Figures 1, 2, 3 and 4 as above described the lifting members 56 engage the bottom surfaces of the shaft portions 12 of the form rollers 9 and lift them up out of the bearings 7 until the shaft portions 12 are at a height such that the inker can be rolled away from the press as above explained without interference by the bearings 7. Thus instead of the inker being moved away from the press leaving the form rollers in posi-

tion in the press the form rollers are carried away along with the inker. This obviates the manual handling of the form rollers and the difficulties in connection therewith which have been explained above.

When the inker is returned to operative position the form rollers come back with it and are replaced in their bearings 7 as shown in Figure 1.

- 10 If it is desired to roll the inker away from the press while leaving the form rollers in their bearings 7 the handle 45 is turned so as to turn the shaft 44 in the counter-clockwise direction viewing Figure 6 about its axis thereby moving the slides 48 to their lefthand positions as shown in Figures 2 and 3. When the slides are thus positioned the lifting members 56 are offset from the shaft portions 12 of the form rollers 9. When the inker is angularly displaced to the position shown in Figure 2 the lifting members 56 simply rise without carrying the form rollers with them, the righthand lifting members 56 rising high enough so that when the inker is rolled away to the left they will pass over top of the 25 ends of the shaft portions 12 of the form rollers 9, leaving the form rollers in place in their bearings 7 as shown in Figures 2 and 3. Figure 2 shows the inker in angularly displaced position ready to be rolled away with the lifting members 30 56 in inoperative position and Figure 3 shows the inker in rolled away position leaving the form rollers 9 in place in their bearings 7. Figures 2 and 4 correspond to each other except that in Figure 4 the lifting members 56 are in operative position and have lifted the form rollers up 35 out of their bearings 7 so that when the inker is rolled away to the left the form rollers will go with the inker, leaving the bearings 7 empty and hence the space therebetween available for work.

- 40 The discs 51 may slide along surfaces of the press frame disposed thereabove or therebelow or both during movement of the inker toward and away from the press, the flattened portions 52 of the discs thus insuring against accidental turning of the shaft 44 while the inker is being rolled out or back. This insures maintenance of the slides 48 and lifting members 56 in their initial position, whichever position that may be, 45 during the entire time when the inker is moving out and back.

- 45 Outside the inker frame the shaft 14 has a pin 58 passing therethrough and projecting outwardly therefrom at both sides. Mounted for 50 sliding movement along the shaft 14 is a handle 59 having at its outer portion a hub 60 slotted at 61 and having at its inner portion and integral therewith a gear 62. An idler pinion 63 rotatably mounted on a stub shaft 64 meshes with a gear 65 fixed to the shaft 33. The handle 59 may be moved axially of the shaft 14 so that either the slots 61 embrace the pin 58 or the gear 62 meshes with the pinion 63. When the handle 59 is in position with the slots 61 embracing the pin 58 and the handle is operated to turn about the axis of the shaft 44 the shaft 44 is turned, resulting in movement of the inker toward or away from the press, depending upon the direction of turning of the handle. When the gear 62 is in mesh with the pinion 63 and the handle is turned it causes turning of the fountain roll 37 through the gear 65.

- 55 While I have shown and described a present preferred embodiment of the invention it is to be distinctly understood that the invention is

not limited thereto but may be otherwise variously embodied within the scope of the following claims.

I claim:

1. Inking mechanism comprising a supporting structure, a form roller carried thereby and removable therefrom, means for delivering ink to the form roller, the ink delivering means being movable into and out of location adjacent the form roller when carried by said supporting structure, support means on the ink delivering means and means carried by the support means and movable relatively thereto to operative position to directly supportingly engage the form roller and remove the same from said supporting structure upon movement of the ink delivering means out of said location and movable relatively to the support means to inoperative position wherein it has no effect on the form roller upon movement of the ink delivering means out of said location.

2. Inking mechanism comprising open form roller bearings, a form roller removably mounted in said bearings, means for delivering ink to the form roller, the ink delivering means being movable into and out of location adjacent the form roller when disposed in said bearings, support means on the ink delivering means and means carried by the support means and movable relatively thereto to operative position to remove the form roller from said bearings upon movement of the ink delivering means out of said location and movable relatively to the support means to inoperative position wherein it has no effect on the form roller upon movement of the ink delivering means out of said location.

3. Inking mechanism comprising upwardly open form roller bearings, a form roller removably mounted in said bearings, means for delivering ink to the form roller, the ink delivering means being movable into and out of location adjacent the form roller when disposed in said bearings, support means on the ink delivering means and means carried by the support means and movable relatively thereto to operative position to lift the form roller upwardly out of said bearings upon movement of the ink delivering means out of said location and movable relatively to the support means to inoperative position wherein it has no effect on the form roller upon movement of the ink delivering means out of said location.

4. Inking mechanism comprising a supporting structure, a form roller carried thereby and removable therefrom, means for delivering ink to the form roller, the ink delivering means being shiftable by movement comprising substantially horizontal movement into and out of location adjacent the form roller when carried by said supporting structure, support means on the ink delivering means and means carried by the support means movable relatively thereto to operative position to directly supportingly engage the form roller and remove the same from said supporting structure upon shifting of the ink delivering means out of said location and movable relatively to the support means to inoperative position wherein it has no effect on the form roller upon shifting of the ink delivering means out of said location.

5. Inking mechanism comprising a supporting structure, a form roller carried thereby and removable therefrom, means for delivering ink to the form roller, a track, the ink delivering means being shiftable by movement comprising movement substantially along the track into and out

of location adjacent the form roller when carried by said supporting structure, support means on the ink delivering means and means carried by the support means and movable relatively thereto to operative position to directly supportingly engage the form roller and remove the same from said supporting structure upon shifting of the ink delivering means out of said location and movable relatively to the support means to inoperative position wherein it has no effect on the form roller upon shifting of the ink delivering means out of said location.

6. Inking mechanism comprising a supporting structure, form roller means carried thereby and removable therefrom, means for delivering ink to the form roller means, the ink delivering means being movable into and out of location adjacent the form roller means when carried by said supporting structure and during such movement being angularly displaceable, support means on the ink delivering means, and means carried by the support means and movable relatively thereto to operative position to engage the form roller means and remove the same from said supporting structure upon angular displacement of the ink delivering means and movable relatively to the support means to inoperative position wherein it has no effect on the form roller means upon angular displacement of the ink delivering means.

7. Inking mechanism comprising a supporting structure, form roller means carried thereby and removable therefrom, means for delivering ink to the form roller means, the ink delivering means being movable into and out of location adjacent the form roller means when carried by said supporting structure and having a portion which during such movement is generally vertically displaceable, support means on said portion and means carried by the support means movable relatively thereto to operate position to engage the form roller means and remove the same from said supporting structure upon generally vertical displacement of said portion and movable relatively to the support means to inoperative position wherein it has no effect on the form roller means upon generally vertical displacement of said portion.

8. Inking mechanism comprising a supporting structure, form roller means carried thereby and removable therefrom, means for delivering ink to the form roller means, the ink delivering means being movable into and out of location adjacent the form roller means when carried by said supporting structure and during such movement being sequentially angularly and linearly displaceable, support means on the ink delivering means and means carried by the support means and movable relatively thereto to operative position to engage the form roller means and remove the same from said supporting structure upon angular displacement of the ink delivering means and movable relatively to the support means to inoperative position wherein it has no effect on the form roller means upon angular displacement of the ink delivering means.

9. Inking mechanism comprising a supporting structure, form roller means carried thereby and removable therefrom, means for delivering ink to the form roller means, the ink delivering means being movable into and out of location adjacent the form roller means when carried by said supporting structure, support means on the ink delivering means, an operating member mounted on the support means and means for shifting the operating member relatively to the support means

between operative position wherein the operating member is adapted to engage the form roller means and remove the same from said supporting structure upon movement of the ink delivering means out of said location and inoperative position wherein the operating member has no effect on the form roller means upon movement of the ink delivering means out of said location.

10. Inking mechanism comprising a supporting structure, form roller means carried thereby and removable therefrom, means for delivering ink to the form roller means, the ink delivering means being turnable into and out of location adjacent the form roller means when carried by said supporting structure, support means on the ink delivering means and an operating member mounted on the support means shiftable relatively to the

support means to position to engage the form roller means and remove the same from said supporting structure upon turning of the ink delivering means out of said location so that when desired the form roller means may be carried with the ink delivering means.
